FOLDABLE DISPLAY PANEL WITH
COLLAPSIBLE SUPPORTJames L. Larkin, Scarsdale, N. Y., assignor to
Forbes Lithograph Manufacturing Company,
Chelsea, Mass., a corporation of Massachusetts

Application January 11, 1944, Serial No. 517,791

10 Claims. (Cl. 40—124.1)

1

This invention relates to displays such as are commonly used in store windows, etc., and which embody a panel suitably decorated as with an attractive picture and with or without accessories supported on the panel, such as auxiliary representations or actual samples of commodities. Such panels are ordinarily provided with an easel or similar support for holding them in an upright position. They are frequently of large dimension such as might suitably be given in terms of feet.

To insure the delivery of the panel in good condition to the user it is necessary to protect the same in transit even although it itself is of heavy cardboard. It has been usual hitherto to provide a separate shipping box of fiberboard or the like.

In accordance with my invention I provide a display comprising a foldable panel and a collapsible support, which latter in erected form serves to hold the panel in upright extended position, the support and panel being proportioned for collocation when collapsed as a flat packet with the folded panel between the parts of the support to be covered and protected thereby throughout its area on both sides. Such a packet requires a mere wrapping of paper to make a shipping package which will insure delivery of the decorated panel to the user in good condition.

My invention will be well understood by reference to the following description of illustrative embodiments thereof shown by way of example in the accompanying drawings, wherein:

Fig. 1 is a perspective view with parts broken away showing the folded panel housed within the collapsed support and requiring merely a paper wrapping to prepare it for shipment;

Fig. 2 is a perspective view showing the support in erected form;

Fig. 3 is a section on line 3—3, of Fig. 2, somewhat enlarged;

Fig. 4 is a back view in perspective of the panel extended;

Fig. 5 is a perspective view of the back of the display as erected for use on a larger scale than Figs. 1, 2 and 4;

Fig. 6 is a detail section, somewhat enlarged, of the lower part of Fig. 5 in the plane of one of the sides 20;

Fig. 7 is a transverse section through Fig. 5;

Fig. 8 is a back view in perspective of a modified form, erected in display position; and

Fig. 9 is a detail section, somewhat enlarged, of

2

the lower part of Fig. 8 in the plane of one of the sides.

In the drawings the panel has been designated as a whole by the reference letter P and the support by the reference letter S. Referring particularly to Figs. 4 and 5, the panel P is a sheet of suitable heavy cardboard bearing the matter to be displayed on its front face, not seen in the drawings, and divided by one or more transverse fold lines 10 into strips 12 capable of being folded together in superposed relation to provide a flat packet as seen in Fig. 1. The end portions of the strips 10 may have vertical fold lines 14 defining the lateral flange portions 16 which when the parts are erected (see Figs. 5 and 7) may be folded rearwardly to provide stiffening flanges for the extended panel. A similar flange 18 may be provided at the upper end of the panel which, bent more or less to the rear out of the plane of the panel, stiffens the upper edge. The construction of panel as so far described is not in itself new.

The collapsible support S for the panel is constructed of heavy fiberboard and, when erected, forms a prismatic column (see Fig. 5), herein a triangular prism and therefore of indeformable cross section. As best seen in Fig. 2, the support S comprises two sides 20 hinged together along two of their edges corresponding to the vertex of a triangle and provided at opposite edges of the sides with the flanges 22 and 24 adapted to overlap and to be interlocked (see Fig. 3) by opposed slots in the edges thereof mutually interengaging in the manner of a halving joint to form a relatively short base for the triangle. The result is a hollow rigid column. When the flanges 22 and 24 are disengaged, they may be turned inwardly between the sides 20 which fold in a superposition to form a folio. The strips 12 of the panel P are of no greater dimension than these sides 20

so that the folded panel may be received within said folio in the manner illustrated in Fig. 1 to be covered and protected thereby throughout its area on either side. The collapsed elements when so collocated, as seen in Fig. 1, form together a flat packet which may be enclosed in a paper wrapping to form a shipping package and in which the support S, which is not on view when the display is erected in use, protects the more readily damaged panel against breakage, bending or abrasion.

To use the display the support S is erected in the manner shown in Fig. 2 and placed in position with the side herein formed by the flanges 22 and 24 opposed to the back of the panel and 55 traversing the fold lines 10. The two parts may

then be secured together at either end of the column. The column serves to hold the panel extended, acting in the manner of a cleat across the folds 10, and it also, as seen in Fig. 5, is a support in the nature of an easel to hold the extended panel upright.

In the embodiment of the invention shown the lower ends of the sides 20 at the rear (see Fig. 5) are provided with diagonal fold lines defining flat portions 26 which may be folded outwardly to form feet contributing to the stability of the structure, while the diagonal position of the fold lines provides a suitable rearward inclination to the support, as shown in Fig. 5. Forward of these flaps the sides are cut away to provide tongues 28 (see Fig. 6) which interlock with slots 30 formed in a rearwardly foldable section 32 at the lower edge of the panel P. The edges of this section may also be provided with notches 34 in line with the slots to embrace the cut-away edges of the sides rearwardly of the tongues 28. By the means described or their equivalents the section 32 is positioned in intersecting relation to the sides 20.

In the embodiment of the invention shown the means for securing the panel at the upper end of the column is different from that at the lower end and comprises a piece 36 secured to the back of the uppermost strip 12 of the panel and having a rearwardly unfolding free flap shaped to present inwardly facing hook-like tongues 38 (see Fig. 7) adapted to extend at either side of the columnar support S and enter slots formed in the sides 20.

We may suppose that the user receives the display in knock-down form as a flat packet in a paper wrapping. The wrapping being removed, the parts are as shown in Fig. 1. The panel is taken out from the support which encloses the same and is laid out flat, face downwardly, as shown in Fig. 4, while the support is folded up into prismatic form, as shown in Fig. 2, and secured by interlocking the flanges 22 and 24. The support is then placed with the base of the triangle down, that is, inverted from the position shown in Fig. 2, against the back of the extended panel as shown in Fig. 4, the upper end of the prism entering the space between the hooks 38. The bottom flange 32 is folded up and the slots 30 are engaged over the tongues 28. The hooks 38 are folded rearwardly and their points entered through the slots in the sides 20 of the support S as illustrated in Fig. 5. The feet 26, if present, are bent outwardly to the position shown in Fig. 5 and the structure stood up as shown in that figure. The flanges 16 and 18, if present, are bent rearwardly to stiffen the margins of the panel and the display is ready for exhibition.

In the modified form of the invention shown in Figs. 8 and 9 parts corresponding generally in structure or function to those of the form shown in Figs. 1 to 7 are designated by the same reference numeral increased by 100. Thus the panel P' has one or more fold lines 110 defining the strips 112 corresponding to the strips 12 between the fold lines 10 in Fig. 5.

The support S' has sides 120 which form a folio of sufficient size to receive between them the collapsed panel with the strips 112 folded together in superposition and, in the erected position shown in the drawing, these two sides extend dihedrally in a position corresponding to adjacent sides of a triangular prism with the third side along the back of the extended panel. The edges of these sides 120 remote from the hinge line between them may be provided with flanges 122 and 124 but in the arrangement shown in Fig. 8 these are

not directly connected together to form a third side of the prism. They may be folded into the plane of the back of the extended panel, as illustrated in the drawings, herein outwardly, and their edges may be tucked under tabs 138 formed by the unattached edge portions of strips secured to the back of the panel and providing a frictional clamping device for holding the flanges with the sides 120 angularly disposed.

- 10 To further secure together the panel and the support and to aid in maintaining the flanges engaged under the tabs 138 the panel may be provided with a rearwardly folding bottom section 132 which when so folded rearwardly intersects the sides 120 and herein the sides are provided with slots 127 into which the section 132 enters and (see Fig. 9) one wall of the slot is here shown as provided with a projection 128 to jam frictionally against the section 132 to aid 15 in relatively positioning the parts. This is a frictional engagement, whereas in Fig. 6 the corresponding projection 28 is sufficiently long to enter a slot 30 to provide a positive engagement.

The sides 120 are shown in Fig. 8 as provided 20 with diagonal fold lines providing portions 126 foldable outwardly to form feet like the feet 26 in Fig. 5.

I am aware that the invention may be embodied 25 in other specific forms without departing from the spirit or essential attributes thereof, and I therefore desire the present embodiment to be considered in all respects as illustrative and not restrictive, as is in fact clear in several matters from the description itself. Reference is to be 30 had to the appended claims to indicate those principles of the invention exemplified by the particular embodiment described and which I desire to secure by Letters Patent.

- I claim:
- 40 1. A display comprising a panel having transverse fold lines defining strips foldable together in superposed relation to provide a flat packet and a separable support comprising sides of a length as great as the width of the panel and a width as 45 great as that of said strips to receive between them when folded into opposition the packet aforesaid, the length of the sides of the support being such as to permit them to extend along the back of the panel across said fold lines, and interengaging 50 means at the ends of said sides and adjacent the upper and lower ends of the panel respectively serving to position the support with its sides angularly disposed as a prismatic column along the back of the panel and crossing the fold lines of 55 the same.

2. A display comprising as separable units a support of sheet material comprising a pair of vertical sides hingedly connected along one pair of edges to fold into superposition and a panel 60 comprising a number of foldably connected strips of no greater dimension than the sides whereby the panel with its strips folded together may be housed between the sides of the support as a flat packet, and means for detachably securing together the extended panel and the support with the sides of the latter dihedrally disposed behind the former and crossing the fold lines thereof.

- 65 3. A display comprising as separable units a support of sheet material comprising a pair of vertical sides hingedly connected along one pair of edges to fold into superposition and a panel comprising a number of foldably connected strips of no greater dimension than said sides, and means for securing the extended panel to the 70 erected support with the latter crossing the fold

lines between the strips and with its sides extending rearwardly from the extended panel, and means for interengaging the erected support with the extended panel which, when interengaged, positions in spaced relation said sides of the support at a pair of edges other than the edges where they are hinged together.

4. A display comprising as separable units a support of sheet material comprising a pair of vertical sides hingedly connected along one pair of edges to fold into superposition, said sides including portions foldable laterally therefrom to provide feet for the support in the latter position, and a panel comprising a number of foldably connected strips of no greater dimension than said sides, and means for securing the extended panel to the erected support with the latter crossing the fold lines between the strips and with its sides extending rearwardly from the extended panel, and means for interengaging the erected support with the extended panel which, when interengaged, positions in spaced relation said sides of the support at a pair of edges other than the edges where they are hinged together.

5. A display comprising a support of sheet material comprising a pair of vertical sides hingedly connected along one pair of edges to fold into superposition and a panel comprising a number of foldably connected strips of no greater dimension than said sides, and means for securing the extended panel to the erected support with the latter crossing the fold lines between the strips and with its sides extending rearwardly from the extended panel in angular relation one to another, said means comprising at least one end of the display an edge portion of the panel foldable as a rearwardly extending flange to intersect the sides of the support, the flange and sides having conformations for retaining them together in such intersecting relation.

6. A display comprising a collapsible prismatic supporting column of sheet material including two sides hingedly connected along one pair of edges to fold into superposition and having foldable flanges at the other edges with provision for locking them together to provide a third side, a panel comprising a number of relatively foldable strips of no greater dimension than said sides, and tongue and slot connections for securing the unfolded panel at said third side of the column with the fold lines between the strips transverse to the height of the column comprising elements cut from said sides and elements associated with the panel to fold rearwardly therefrom to connect with the former.

7. A display comprising as separable units a support of sheet material comprising a pair of vertical sides hingedly connected along one pair of edges to fold into superposition and a panel comprising a number of foldably connected strips of no greater dimension than the sides whereby the panel with its strips folded together may be housed between the sides of the support as a flat packet, and means for detachably securing together the extended panel and the support with the sides of the latter dihedrally disposed behind the former and crossing the fold lines thereof including hook-like members hinged at the rear of the panel and adapted to be engaged with the angularly disposed sides.

8. A display comprising as separable units a support of sheet material comprising a pair of vertical sides hingedly connected along one pair of edges to fold into superposition and a panel comprising a number of foldably connected strips of no greater dimension than the sides whereby the panel with its strips folded together may be housed between the sides of the support as a flat packet, and means for detachably securing together the extended panel and the support with the sides of the latter dihedrally disposed behind the former and crossing the fold lines thereof comprising flanges at the edges of said sides remote from those which are hinged together, which flanges fold into the plane of the extended panel, the back of the panel having tabs beneath which the flanges tuck when the sides are angularly disposed.

9. A display comprising as separable units a support of sheet material comprising a pair of vertical sides hingedly connected along one pair of edges to fold into superposition and a panel comprising a number of foldably connected strips of no greater dimension than the sides whereby the panel with its strips folded together may be housed between the sides of the support as a flat packet, and means for detachably securing together the extended panel and the support with the sides of the latter dihedrally disposed behind the former and crossing the fold lines thereof comprising flanges at the edges of said sides remote from those which are hinged together, which flanges fold into the plane of the extended panel, the back of the panel having elements thereon with unattached edges forming tabs beneath which the flanges tuck when the sides are angularly disposed.

10. A display comprising as separable units a support of sheet material comprising a pair of vertical sides hingedly connected along one pair of edges to fold into superposition and a panel comprising a number of foldably connected strips of no greater dimension than the sides whereby the panel with its strips folded together may be housed between the sides of the support as a flat packet, and means for detachably securing together the extended panel and the support with the sides of the latter dihedrally disposed behind the former and crossing the fold lines thereof comprising flanges at the edges of said sides remote from those which are hinged together, which flanges fold into the plane of the extended panel, and means for clamping the flanges against the back of the panel with the sides in angular relation.

JAMES L. LARKIN.
